UNITED STATES PATENT OFFICE.

ONNIK TAKVORIAN, OF BOSTON, MASSACHUSETTS.

DESIGN FOR WRAPPED CANDY.

SPECIFICATION forming part of Design No. 28,672, dated May 17, 1898.

Application filed August 14, 1897. Serial No. 648,330. Term of patent 14 years.

To all whom it may concern:

Be it known that I, ONNIK TAKVORIAN, of Boston, in the county of Suffolk and State of Massachusetts, have invented and produced a new and original Design for Wrapped Candy, of which the following is a description.

In the drawings, Figure 1 represents a perspective view of a piece of wrapped candy embodying my design. Fig. 2 represents a longitudinal section of the same. Fig. 3 represents a transverse cross-sectional view of the same.

As shown in the drawings, the leading or material feature of my design consists of a flat rectangular wrapped body of candy having rounded side edges and substantially sharp end edges, the edges of the wrapper being flush with the ends of the body of the candy.

The wrapped body of candy as a whole is 20 indicated in the drawings at *a*, the rounded long side edges being indicated at *b*, and the end edges, which are tapering, so as to form substantially sharp terminations of the body, are indicated at *c*. 25

Having now described my design, what I claim is—

The design for wrapped candy, substantially as herein shown and described.

In testimony whereof I have signed my 30 name to this specification, in the presence of two subscribing witnesses, this 13th day of August, A. D. 1897.

ONNIK TAKVORIAN.
